UNITED STATES PATENT OFFICE.

ALFRED EXTRAND, OF ABERDEEN, WASHINGTON.

TORPEDO.

1,212,468.

Specification of Letters Patent. Patented Jan. 16, 1917.

Application filed August 14, 1915. Serial No. 45,542.

To all whom it may concern:

Be it known that I, ALFRED EXTRAND, a citizen of the United States, and a resident of Aberdeen, in the county of Chehalis and 5 State of Washington, have invented certain new and useful Improvements in Torpedoes, of which the following is a description.

The invention relates to improvements in torpedoes of the automobile type, and it has 10 for one of its objects the provision of steering means whereby the course of the torpedo can be controlled from the parent vessel.

It also has for its object the provision of means for returning the torpedo to its 15 parent vessel should it miss its objective mark, said returning means being also controlled from the parent vessel.

It further has for its object the provision of a signal mounted on the torpedo, and 20 under control from the parent vessel, whereby the course of the torpedo can be readily followed only by the observer on the parent vessel.

Another object of the invention is to provide in the parent vessel a locking chamber from which the torpedo is started that is particularly adapted to the steering means 25 for controlling the course of the torpedo.

The invention consists in the novel construction, combination, and arrangement of parts hereinafter described, illustrated by the accompanying drawings, and pointed out in the appended claims.

In the drawings, in which similar reference characters designate corresponding parts, Figure 1 is a perspective view, showing the torpedo leaving the parent vessel. Fig. 2 is a view showing a horizontal section of the locking chamber, and the mechanism 30 for operating the steering lines. Fig. 3 is a detail sectional view of a part of the locking chamber, and the line controlling the signal. Fig. 4 is a detail perspective view showing the signal mounted on the 35 torpedo. Fig. 5 is a side elevation, partly in section and partly broken away, showing the torpedo.

The parent vessel 1 may be of the submarine type, as shown in the drawing. In the 40 forward side of the vessel is the lock chamber 2 from which the torpedo is discharged. The inner and outer ends of the chamber are provided with the usual slide doors to control the openings of the chamber. To the 45 rear of the lock chamber is mounted the

shaft 3 driven by the belt 4 from the motor 5. Rotatable on the shaft are the winding drums 6, 6^a, each of which is provided with a clutch 7 by means of which motion can be imparted from the shaft to the drum, and each drum is provided with a friction brake 8 by means of which the rotation of the drums on the shaft can be controlled. On the drums 6, 6^a are respectively wound the 60 lines 9, 9^a passing through the laterally adjustable guides 10, by means of which the lines are played onto the drums as they are wound thereon.

The torpedo 11 is of the usual automobile type and is discharged from the lock chamber 2. Leading through the rear wall of the lock chamber are the lines 9, 9^a, the outer ends of which are secured to the opposite sides of the torpedo, as at 12. In operating the torpedo, the outer door of the lock chamber is first closed and after the water has escaped from the chamber in the usual manner the inner door is opened and the torpedo is placed within the chamber and the lines 9, 9^a are attached to its sides. When the 70 torpedo is launched, after the propelling mechanism has been started, the inner door of the lock chamber is closed and the outer door is open to give access to the outside 75 water. When the chamber fills the torpedo passes outwardly from the lock chamber toward its objective point. The progress of the torpedo can be followed by a signal 80 mechanism hereinafter described.

By manipulating the lines 9, 9^a the torpedo can be guided in its course. Before the torpedo is launched the clutches 7 are moved to free the drums 6, 6^a so that the latter can turn freely on the shaft 3. As the torpedo 85 progresses the lines are drawn off their drums. Should it be desired to change the course of the torpedo, say to the right as shown in Fig. 1, by a slight application of the brake 8 to the drum 6, a slight pull will 90 be given to the line 9 which will tend to turn the torpedo to the right. When the torpedo has been sufficiently turned to the desired 95 course the brake is released and the line 9 is freed from the pull so that the tension of both lines will be the same. To turn the 100 torpedo to the left, the drum 6^a and the line 9^a are manipulated in the same way. Should the torpedo not reach its target it can be recovered by moving the clutches 7 to connect the drums 6, 6^a with the shaft 3, which 105

is driven by the motor 5, to wind in the lines 9, 9^a. By moving the guides 10 back and forth while the lines are being wound in the latter are played onto the drum so as to be wound smoothly thereon. As the drums are of the same diameter and are driven at the same rate of speed, and the lines being of an equal length, they will be retrieved at the same rate of travel and thereby tangling 10 of the same will be avoided.

Mounted on the torpedo is a visual signal, operated from the parent ship, whereby the course of the torpedo can be followed by observers on the parent ship. On the upper surface of the torpedo is mounted the telescopic standard 13 carrying at its upper end an electric lamp. The lower end of the standard is hinged to the torpedo, as at 14, so that the standard can be turned forward 20 down onto the body of the torpedo. The turning down of the standard is to facilitate the return of the torpedo into the lock-chamber. In its upright position the standard rests against the block 15, which holds 25 it in such position against the pressure of the water as the torpedo moves forward. To prevent the standard from accidentally falling forward the spring 16 is provided that tends normally to hold the standard in 30 an upright position. The two telescopic members of the standard are normally pressed to an extended position by the compressed coiled spring 17. Over the electric lamp is the hood 18 only open at the rear 35 so that the light can only be seen from astern of the torpedo.

The two members of the standard can be telescoped by the line 19 secured to the upper member and passing under the pulleys 40 20. This line leads from the torpedo through the top of the lock chamber, as at 21, to the drum 22 loosely journaled on the shaft 24 mounted back of the shaft 3. The shaft 24 is driven by the belt 25 leading 45 from the motor 5. A clutch 26 is provided for connecting and disconnecting the drum 22 with the shaft 24, and a friction brake 27 is provided so that the turning of the drum can be retarded. A guide 28 is provided 50 for the line 19 so that it can be played smoothly onto the drum 22 while being wound thereon. The drum 22 is driven at the same rate of speed as the drums 6, 6^a, so that the three lines will be wound in at 55 the same rate.

While the torpedo is traveling toward its mark a slight pressure is applied to the friction brake 27 so as to retard slightly the paying out of the line 19. This slight restraint on the line will exert a sufficient pull 60 on the upper member of the standard 13 as to telescope the same against the action of the spring 17. As the torpedo travels

slightly below the surface of the water, the telescoped standard will be submerged. 65

Should it be desired to ascertain the position of the torpedo, the pressure of the brake 27 on the drum 22 is relieved and the line 19 permitted to run free. When the restraint on line 19 is removed, the spring 17 70 extends the telescopic standard so as to project the signal at its upper end above the surface of the water. When it is dark the electric lamp, which can only be seen from astern of the torpedo, will indicate to the 75 observer on the parent ship the position of the torpedo; also, during daylight the projecting end of the standard will designate the position. The exposure of the signal need only be sufficiently long to enable the 80 location of the torpedo. As soon as the position is located the movement of the line 19 is again restrained to telescope the members of the standard and thereby cause the signal to disappear. By exposing the signal 85 at intervals during the travel of the torpedo, its course can be guided toward its objective mark. Should the torpedo miss its mark, in retrieving the same all three of the lines 90 would be wound onto their respective drums at the same rate of speed to prevent entanglement.

Having thus described my invention, what I claim and desire to secure by Letters Patent is:

1. The combination of a parent vessel provided with a lock-chamber, an automobile torpedo adapted to be launched from the lock-chamber, lines for guiding and retrieving the torpedo extending from the parent vessel through the lock-chamber and laterally attached to the torpedo, a depressible signal mounted on the torpedo, a line leading from the parent vessel through the lock-chamber to the signal, a winding mechanism on the parent vessel operating to simultaneously wind and unwind the guiding and signal lines, and means for varying the tension on said lines to guide the torpedo and to depress the signal. 100

2. The combination of a parent vessel provided with a lock-chamber, an automobile torpedo adapted to be launched from the lock-chamber, a telescopic signal mounted on the torpedo, a spring normally extending the telescopic signal, a line leading from the movable member of the telescopic signal to the parent ship, means on the parent ship for paying out the line during the progress of the torpedo, and means for restraining the line to telescope the movable member of the signal against the action of said spring. 115

In testimony whereof I hereunto affix my signature.

ALFRED EXTRAND.
